US00D887147S

(12) **United States Design Patent** (10) **Patent No.:** **US D887,147 S**
(45) **Date of Patent:** **** Jun. 16, 2020**

(54) **ORAL CARE IMPLEMENT**

- (71) Applicant: **Colgate-Palmolive Company**, New York, NY (US)
- (72) Inventor: **Eduardo Jimenez**, Manalapan, NJ (US)
- (73) Assignee: **Colgate-Palmolive Company**, New York, NY (US)
- (**) Term: **15 Years**
- (21) Appl. No.: **29/614,256**
- (22) Filed: **Aug. 17, 2017**

Related U.S. Application Data

- (62) Division of application No. 29/549,087, filed on Dec. 18, 2015, now Pat. No. Des. 798,061.

(57) **CLAIM**

The ornamental design for an oral care implement, as shown and described.

DESCRIPTION

FIG. 1 is a front right perspective view of an oral care implement according to a first embodiment of the new design;

FIG. 2 is a rear left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front right perspective view of an oral care implement according to a second embodiment of the new design;

FIG. 10 is a rear left perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The difference in grayscale shading represents surfaces having a contrast in appearance as shown.

1 Claim, 8 Drawing Sheets
